BAKING MOLD

May MacGregor, New York, N. Y.

Application April 2, 1952, Serial No. 19,161

Term of patent 7 years

(Cl. D44—1)

To all whom it may concern:

Be it known that I, May MacGregor, a citizen of the United States of America, residing at New York city, in the county and State of New York, have invented a new, original and ornamental Design for a Baking Mold, of which the following is a specification, reference being had to the accompanying drawing, forming a part thereof.

Fig. 1 is a top plan view of a baking mold, showing my new design;

Fig. 2 is a longitudinal vertical sectional view on line 2—2 of Fig. 1; and

Fig. 3 is an end elevational view thereof, partly broken away.

The dominant feature of my design resides in the ornamental figure appearing in the bottom of the mold, as shown.

I claim:

The ornamental design for a baking mold, substantially as shown and described.

MAY MACGREGOR.
